(57) **CLAIM**

The ornamental design for a mood light, as shown and described.

DESCRIPTION

FIG. 1 is a perspective view of a mood light showing my new design;

FIG. 2 is a front view thereof;

FIG. 3 is a back side view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof when the moon light is upside down.

The broken lines in the drawings illustrate portions of the mood light and form no part of the claimer design.
